US00D879593S

(12) United States Design Patent (10) Patent No.: US D879,593 S
 Boies et al. (45) Date of Patent: * Mar. 31, 2020

(54) HOSE REEL(71) Applicant: GARANT GP, Saint-François (CA)

(72) Inventors: David Boies, Lévis (CA);
Marie-Claude Guay, Lac Beauport (CA); Alexandre Allard, Quebec (CA); Mario Gagnon, Ste-Adèle (CA); Romain Zolfo, Montreal (CA); Benoit Orban, Saint-Lambert (CA); André Quevillon, Blainville (CA)

(73) Assignee: GARANT GP (CA)() Term: 15 Years(21) Appl. No.: 29/632,466(22) Filed: Jan. 8, 2018(51) LOC (12) Cl. .... 08-05(52) U.S. Cl. D8/359
USPC ....(58) Field of Classification Search

CLAIM

The ornamental design for a hose reel, as shown and described.

DESCRIPTION

FIG. 1 is perspective view of a hose reel showing our new design;

FIG. 2 is a first side view thereof;

FIG. 3 is a second side view thereof;

FIG. 4 is a front view thereof;

FIG. 5 is a rear view thereof;

FIG. 6 is a top view thereof; and,

FIG. 7 is a bottom view thereof.

The broken lines shown in FIGS. 1-7 depict portions of the hose reel that form no part of the claimed design.
